UNITED STATES PATENT OFFICE

95,378

DESIGN FOR A LAVATORY

John Richard Morgan, Oak Park, Ill., assignor to
Sears, Roebuck & Company, Chicago, Ill., a
corporation of New York

Application February 1, 1935, Serial No. 55,197

Term of patent 14 years

To all whom it may concern:

Be it known that I, John Richard Morgan, a subject of the King of England, residing at Oak Park, in the county of Cook and State of Illinois, have invented a new, original, and ornamental Design for a Lavatory, of which the following is a specification, reference being had to the accompanying drawing, forming part thereof.

In the drawing, the figure is a perspective view of the lavatory, showing my new design.

The dominant feature of my design consists in the lavatory shown in full lines, the pedestal shown in dotted lines being an immaterial feature.

I claim:

The ornamental design for a lavatory, substantially as shown and described.

JOHN RICHARD MORGAN.
